(57) **CLAIM**

The ornamental design for a floor lamp, as shown and described.

DESCRIPTION

FIG. 1 is a front, left, top isometric view of the floor lamp;
 FIG. 2 is a front elevation view of the floor lamp;
 FIG. 3 is a back elevation view of the floor lamp;
 FIG. 4 is a left side elevation view of the floor lamp;
 FIG. 5 is a right side elevation view of the floor lamp;
 FIG. 6 is a top plan view of the floor lamp; and,
 FIG. 7 is a bottom plan view of the floor lamp.
 The broken lines in the figures show portions of the floor lamp that form no part of the claimed design.
